(57) **CLAIM**

The ornamental design for an inflatable pool lounger as shown and described.

DESCRIPTION

FIG. 1 is a top front isometric view of an inflatable pool lounger.

FIG. 2 is a front side elevation view thereof.

FIG. 3 a back side elevation view thereof.

FIG. 4 is a left side elevation view thereof

FIG. 5 is a right side elevation view thereof.

FIG. 6 is a top plan view thereof.

FIG. 7 is a bottom plan view thereof.

FIG. 8 is a cross section taken along lines 8-8 of FIG. 6.

FIG. 9 is a top front isometric view of a second embodiment of an inflatable pool lounger.

FIG. 10 is a front side elevation view thereof.

FIG. 11 a back side elevation view thereof.

FIG. 12 is a left side elevation view thereof

FIG. 13 is a right side elevation view thereof.

FIG. 14 is a top plan view thereof.

FIG. 15 is a bottom plan view thereof.

FIG. 16 is a cross section taken along lines 16-16 of FIG. 14.

FIG. 17 is a top front isometric view of a third embodiment of an inflatable pool lounger.

FIG. 18 is a top front isometric view of an inflatable pool lounger.

FIG. 19 is a front side elevation view thereof.

FIG. 20 a back side elevation view thereof.

FIG. 21 is a left side elevation view thereof.

FIG. 22 is a right side elevation view thereof.

FIG. 23 is a top plan view thereof.

FIG. 24 is a bottom plan view thereof; and,

FIG. 25 is a cross section taken along lines 24-24 of FIG. 22.

The portions of the object shown in broken lines depict portions of the article and unclaimed borders and form no part of the claimed design.

1 Claim, 19 Drawing Sheets
